UNITED STATES PATENT OFFICE.

CHARLES J. JOHNSON, OF CHICAGO, ILLINOIS.

PNEUMATIC ACTION.

1,157,398.

Specification of Letters Patent. Patented Oct. 19, 1915.

Application filed January 24, 1914. Serial No. 314,159.

To all whom it may concern:

Be it known that I, CHARLES J. JOHNSON, a citizen of the United States, and a resident of the city of Chicago, county of Cook, and State of Illinois, have invented certain new and useful Improvements in Pneumatic Actions, of which the following is a specification.

My invention relates to improvements in pneumatic actions especially adapted for use in player pianos and has for its object the provision of an improved construction of this character which is simple and efficient in use.

The invention consists in the combinations and arrangements of parts hereinafter described and claimed.

The invention will be best understood by reference to the accompanying drawings forming a part of this specification, and in which—

Figure 1 is a face view of a portion of the pneumatic action of a player piano shown with portions broken away and others in section, and Fig. 2 is a section taken on line $x-x$ of Fig. 1.

The preferred form of construction as illustrated in the drawings comprises a plurality of bellows 1, each having a movable side 2 connected with a separate operating rod 3, each of the rods 3 being adapted to operate one note of a piano (not shown). The bellows 1 are preferably arranged in three rows, but connected to operate independently of each other. An air chamber 4 is arranged adjacent each of the bellows 1 and in open communication with the outside atmosphere through a passage 6 and a port 7 as shown. A vacuum chamber 8 is arranged across the front of the bellows 1 and air chambers 4 and a port 9 leads from chamber 8 into each of the air chambers 4. The vacuum chamber 8 is formed in a space between a front board 10 and a rear board 11 which are spaced apart at the bottom by means of a strip 12 and are secured together at the top by means of a top board 13. An angular valve head 14 is arranged in each of the chambers 4 and carries two valves 15 and 16, valve 15 being arranged to hold the corresponding port 9 normally closed and valve 16 being arranged to close port 7 when valve head 14 swings to open port 9. Valve head 14 is mounted upon a piece of flexible fabric 17, such as rubber cloth, and secured in place

against the top of the corresponding air chamber 4 by means of a plate 18 as indicated. Arranged in board 10 immediately in front of each of the chambers 4 is an intermittent vacuum chamber 19 which is separated from chamber 8 by means of a flexible diaphragm 20, each of the chambers 19 being connected by a passage 21 in top board 13 with the flexible tube 22 leading to the usual tracker board of the player piano. Arranged across the upper front portion of board 10 is a bleeder vacuum chamber 23 which is in constant communication with each of the chambers 19 through a minute bleeder opening 24. A rod 25 is slidably mounted in a suitable bracket 26 and contacts with the corresponding diaphragm 20 and the corresponding valve 15, so that inward movement of diaphragm 20 into chamber 8 will raise valve 15 from its seat and swing valve 16 to its seat.

In operation a vacuum is maintained in each of the chambers 8 and 23 in the usual manner. When air is admitted to any one of the chambers 19 through the corresponding tube 22 from the tracker board of the piano, the vacuum normally maintained in said chamber 19 is wholly or partially destroyed and diaphragm 20 is drawn inwardly in chamber 8 by the vacuum maintained therein. This opens the corresponding valve 15 and closes the corresponding valve 16 so that a vacuum is also formed in the corresponding chamber 4 causing collapse of the bellows 1 and elevation of the rod 3. This upward movement of rod 3 is its operative stroke. When the admission of air through tube 22 is discontinued, the constant bleeding or passage of air through minute opening 24 into chamber 23 reestablishes a vacuum in the corresponding chamber 19 and as soon as the pressure in chamber 19 falls below that of the outside atmosphere the pressure of the atmosphere on valve 16 combined with gravity will open said valve 16 and close valve 15 thus restoring the parts to original normal condition.

The arrangement disclosed is a simple and efficient one for the purpose, very compact in form, is practically unaffected by changes in temperature and therefore is highly efficient in use.

While I have illustrated and described the preferred form of construction for carrying my invention into effect, this is capable

of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

A pneumatic action comprising an air chamber having ports in adjacent walls thereof; a swinging valve head carrying two valves in fixed relation to each other and

controlling said ports, said valve head being supported by a flexible member secured to a wall of said air chamber by means of a removable plate; and means for swinging said valve head to cause said valves to control said ports to effect operation of said pneumatic, substantially as described.

In testimony whereof I have signed my name to this specification in the presence of two subscribing witnesses.

CHARLES J. JOHNSON.
